UNITED STATES PATENT OFFICE.

WILLIAM H. DODSON, JR., OF SAN ANTONIO, TEXAS.

DESIGN FOR A SEAT MEMBER FOR FLOAT-VALVES.

SPECIFICATION forming part of Design No. 35,188, dated October 15, 1901.

Application filed June 13, 1901. Serial No. 64,462. Term of patent 7 years.

To all whom it may concern:

Be it known that I, WILLIAM H. DODSON, Jr., a citizen of the United States, residing at San Antonio, in the county of Bexar and State 5 of Texas, have invented and produced a new and original Design for a Seat Member for Float-Valves, of which the following is a specification, reference being had to the accompanying drawings, forming a part thereof.

10 In the drawings, Figure 1 is a side elevation, and Fig. 2 is a perspective view thereof.

The material feature of my design embraces a valve-seat A, having an angulated base a' , from the rear side of which base is 15 projected upwardly above the valve-seat a curved arm B, perforated at its upper end to

receive the lever-arm connection. Upon the side of said base a' opposite to the arm B is cast a bracket a , provided with a lug B' for hinging the valve to the valve-seat. 20

Having thus described my invention, what I claim, and desire to secure by Letters Patent, is—

25 The design for a seat member for float-valves herein shown and described.

In testimony whereof I affix my signature in presence of two witnesses.

W. H. DODSON, JR.
